In France September 26, 1946

Section 1, Public Law 690, August 8, 1946

Term of patent 14 years

(Cl. D77—1)

To all whom it may concern:

Be it known that I, Jacques Bernard, citizen of the French Republic, residing at Paris (Seine), France, 64 rue Pergolese, have invented a new, original, and ornamental Design for a Motor Unit, of which the following is a specification, reference being had to the accompanying drawings, forming part thereof.

Fig. 1 is a front view of a motor unit, showing my new design;

Fig. 2 is a side view of said motor unit seen from the right-hand side;

Fig. 3 is a side view of said motor unit seen from the left-hand side;

Fig. 4 is a rear view thereof; and

Fig. 5 is a top plan view thereof.

I claim:

The ornamental design for a motor unit, as shown.

JACQUES BERNARD.
